DESIGN FOR A JAR

Gwynne Evans, St. Louis, Mo., assignor to David G. Evans Coffee Company, St. Louis, Mo., a corporation of Missouri

Application February 24, 1934, Serial No. 50,849

Term of patent 7 years

To all whom it may concern:

Be it known that I, Gwynne Evans, a citizen of the United States, and residing at St. Louis, in the county of St. Louis and State of Missouri, have invented a new, original, and ornamental Design for a Jar, of which the following is a specification, reference being had to the accompanying drawing, forming a part thereof.

In the drawing:

Fig. 1 is a side elevational view of a jar showing my design.

Fig. 2 is a side elevational view taken at right angles to Fig. 1.

Fig. 3 is a side elevational view of the face opposite that shown in Fig. 1.

Fig. 4 is a top plan view.

I claim:

The ornamental design for a jar substantially as shown.

Signed at St. Louis, in the county of St. Louis, and States of Missouri, this 17th day of February, 1934.

Gwynne Evans.
